UNITED STATES PATENT OFFICE.

FRANK A. HOLLENBECK, OF SYRACUSE, NEW YORK, ASSIGNOR TO ROBERT CROASDALE, OF SAME PLACE.

DESIGN FOR A SADDLE-SPRING.

SPECIFICATION forming part of Design No. 28,336, dated March 1, 1898.

Application filed December 21, 1897. Serial No. 662,940. Term of patent 7 years.

To all whom it may concern:

Be it known that I, FRANK A. HOLLENBECK, of the city of Syracuse, county of Onondaga, New York, have invented and produced a new and original Design for a Saddle-Spring, of which the following is a specification.

In the accompanying drawings, Figure 1 is a side view of the said spring, showing my design. Fig. 2 is an end view. Fig. 3 is a plane view looking from the under side.

Similar numerals of reference indicate like parts.

The leading feature of my design consists, in a saddle-spring having twin spirals, of the windings of said spirals in opposite directions and about axes which are at right angles with the lines of the longitudinal portions of the spirals.

The wire or wires 4 and 5 begin at two points 1 and 7 at the rear of the saddle and proceed in curved lines first convergent, then continuing in said curved lines become divergent and descendent and then again convergent, and having formed two spirals proceed in lines parallel with each other and at right angles with a line passing through the two beginning points 1 and 7 until approaching the front end or pommel of the saddle curving upward and convergent meet at 8.

I claim—

The design for a saddle-spring substantially as hereinbefore shown and described.

FRANK A. HOLLENBECK.
